UNITED STATES PATENT OFFICE

NILS D. LEVIN, OF COLUMBUS, OHIO

STOCKING SUPPORTER

Application filed August 17, 1931. Serial No. 557,697.

The present invention relates to stocking supporters, and has for its object to provide a supporter which will relieve the limbs from constriction, with the consequent discomfort and possible impedance of circulation which is a fault with many of the supporters now on the market; which will automatically dispose its parts comfortably to the body of the wearer; and which will equalize during the movements of the wearer to maintain equal pull on the stockings.

The object of the invention is accomplished by providing suitable supporters suspended from a hanger device which in turn is sustained at the crotch of the trousers or other garment of the user in such manner that the device will maintain stockings in proper position without interfering in any way with the comfort of the wearer, and furthermore without in any way disturbing the set of the clothing.

In order that the invention may be understood clearly by those skilled in the art, I have shown in the accompanying drawing one embodiment of my invention, and that the best now known to me, although it will be understood that this disclosure is merely illustrative and in no sense restrictive, and that such changes as are within the range of mechanical skill and design may be made without departing from the range of my invention as defined in the appended claims.

In the drawing:

Figure 1 is a view in perspective showing the device in conventional position.

Figure 2 is a view in cross section on substantially the line 2-2 of Figure 1 to show the crotch hanger.

Figure 3 is a sectional view of the crotch hanger to show the hanger proper, its protective covering, and the freely running loop of the supporter in the hanger.

Figure 4 is an elevational view of a slightly different type of crotch hanger.

Figure 5 is a view in cross section on substantially the line 5-5 of Figure 4.

Figure 6 is a view showing a modified form of connection between parts of the supporter.

Referring to the drawing by numbers, like numbers indicating like parts in the several

views, 10 indicates the stocking engaging members which may be of any known or suitable design, provided with the usual or appropriate clip device 11 to engage the stocking. As here shown, the stocking engaging members 10 are the well-known type of support designed for supporting stockings by a single strand member and without encircling the limbs, the lower clip 11 being attached, as stated, to the stockings, while the upper clip 12, in this form of garter, is intended to be attached to a body garment. The objection to this type of garter is that it does not sufficiently support the stocking or maintain it in proper position, and it creates a drag at two different points on the body garment to which the upper clips 12 are secured, tending to distort or displace the garment from its normal position.

Secured to the upper ends of the stocking engaging members 10 are flexible sustaining strips 13, and while these may be secured in any suitable manner, it may be conveniently done by fastening them to the upper clip members 12 so that the parts may be readily detached for renewal if desired. The flexible sustaining strips 13 will be preferably secured adjustably to the clips 12 of the stocking engaging members 10, and any suitable adjustment may be used, that adjustment, as here shown, being secured by passing the lower ends of the strips 13 about the post of the closed clip and tying or otherwise securing the ends of the strips 13 in the proper position of adjustment, it being understood that the stocking engaging members 10 are elastic, and further adjustment can be secured by means of the adjusting buckles 14 for the members 10 so that the device as a whole will have two points of adjustment, either or both of which may be utilized.

The flexible strips 13 are preferably end portions of a continuous strip which is looped at its top and passed through a crotch hanger 15 made up in any suitable manner, as here shown being made of a metal tube 16 covered with a rubber envelope or tube 17, the ends of which project below the metal tube so as to enclose and protect the wearer from contact with all metal parts. This crotch hanger

may, of course, be adjusted so as to give it more or less spread and direct the flexible sustaining members 13 along the desired lines by simply bending the legs of the crotch hanger outwardly or compressing them to give the desired angle.

The connections between the sustaining members 13 and the stocking engaging members 10 may, of course, be varied within wide limits, another convenient form of connection being shown in Figure 6, in which a clip 18 clamps a portion of the stocking engaging member 10 and the strip 13 together, as shown.

15 The use and operation of the device will be clear from Figure 1.

The crotch hanger 15 being placed in position so as to be supported at the crotch of the garment, the flexible sustaining members 13 will pass downwardly along the inside of the legs of the wearer to the stocking engaging members 10, to the upper ends of which they are secured. The lower clips 11 are preferably engaged with the inside of the

25 stockings so that the stocking engaging and flexible sustaining members will lie in straight lines along the inside of the legs of the wearer. After the suitable adjustments are made for length, they need not be again disturbed until stretching incident to wear occurs, and then the take-up may be made by adjusting the length either at the point where the flexible strips 13 engage the upper clips 12 or at the adjustable buckles 14 on the elastic

30 stocking engaging members 10, or both.

It will be seen that the device is of such construction that no discomfort is occasioned to the wearer, for the crotch hanger 15 is so devised and protected that it will not interfere in any way with the convenience of

40 the user, and its adjustability widthwise by bending or compressing it permits the depending parts carried by it to be directed as to their lines of pull so as to meet the needs

45 of the wearer. Furthermore, the free play of the end loop of the flexible sustaining members 13 permits the parts to move and equalize in response to the movements of

50 the wearer and prevents undue strain either on the crotch hanger or the stocking supporting members. As here shown the flexible sustaining members 13 are round in cross section so that they can turn or swivel in the crotch hanger 15 and permit the stocking engaging

55 members 10, here shown as flat strips, to adjust themselves to the leg and lie flatly and comfortably thereon. Furthermore, such round form of the strips 13 prevent any twisting into folds, as would be the case with flat strips, with consequent discomfort to the wearer.

In Figures 4 and 5 I have shown a modification of the crotch hanger heretofore described, although embodying the same general principle.

In this form the relatively rigid portion 19 is provided, this being preferably made of metal and bent to the appropriate shape, this portion 19 being preferably bendable so as to permit expansion or compression of the crotch hanger. As here shown, the piece 19 is flat, and secured to its edges by stitching or in any suitable manner is an envelope 20 of fabric, which preferably entirely surrounds the piece 19 so that it cannot contact with the wearer, and the fabric envelope 20 also is preferably extended beyond the ends of the piece 19, as shown in Figure 4.

While I have shown and described a metal crotch hanger, it will be understood that such hanger may be made of other materials such as hard rubber, bakelite or other synthetic resinous compounds, or indurated fiber molded to proper size and form.

As pointed out, I do not limit myself to the exact disclosure here shown insofar as that disclosure may be varied within the limits of mechanical skill and design.

I claim:

1. A stocking supporter of the type adapted to be suspended by the crotch of the trousers of the wearer, and having portions extending downwardly of each leg thereof for attachment to each stocking, said supporter comprising a rigid hanger member of material having a low coefficient of friction, a round, elongated cord-like strip of flexible material threaded through said hanger member for free sliding movement therethrough, an elastic strip at each end of said first strip, and stocking engaging means secured to the lower ends of each of said elastic strips, said rigid member of material having a low coefficient of friction serving to facilitate sliding movement of said cord-like strip therethrough, whereby said supporter may adjust itself automatically according to various postures assumed by the wearer.

2. A stocking supporter of the type adapted to be suspended by the crotch of the trousers of the wearer, and having portions extending downwardly of each leg thereof for attachment to each stocking, said supporter comprising a rigid hollow, tubular hanger member of material having a low coefficient of friction, an elongated round, cord-like strip of flexible material having an exterior surface slidably fitting the interior tubular surface of said hanger member and threaded therethrough for free sliding movement, and stocking engaging means at the ends of said strip, said rigid hollow, tubular member of material having a low coefficient of friction serving to facilitate sliding movement of said strip thereover, whereby said supporter may adjust itself automatically according to various postures assumed by the wearer.

3. A stocking supporter of the type adapted to be suspended by the crotch of the trousers of the wearer and having portions

- extending downwardly of each leg thereof for attachment to each stocking, said supporter comprising a rigid tubular hanger member of hard smooth material and having 5 a tubular interior strip supporting surface, an elongated, round, cord-like strip of flexible material slidably supported on said interior surface of said hanger for free sliding movement thereover, elastic members at each end 10 of said cord-like strip, and stocking engaging means at the lower end of each of said members, said hard and smooth surface of said hanger member serving to facilitate sliding movement of said strip thereover, whereby 15 said supporter may adjust itself automatically according to various postures assumed by the wearer.
4. A stocking supporter of the type adapted to be suspended by the crotch of the 20 trousers of the wearer and having portions extending downwardly of each leg thereof for attachment to each stocking, said supporter comprising a tubular metal hanger member having an inverted V-shape, an elongated round cord of flexible material threaded through said hanger member for free sliding movement, flat ribbon-like elastic members 25 connected to opposite ends of said cord, and stocking engaging means at the lower end of each of said members, said metal hanger serving to facilitate sliding movement of said strip thereover, whereby said supporter may adjust itself automatically according to various postures assumed by the wearer.
